UNITED STATES PATENT OFFICE.

ERNEST E. WEBB, OF BALTIMORE, MARYLAND, ASSIGNEE, BY DIRECT AND MESNE ASSIGNMENTS, OF ONE-THIRD TO GEORGE D. FRYFOGLE AND ONE-THIRD TO EUGENE H. TIMANUS, BOTH OF BALTIMORE, MARYLAND.

ATTACHMENT FOR LOOMS.

1,390,943.

Specification of Letters Patent. Patented Sept. 13, 1921.

Application filed December 26, 1919. Serial No. 347,301.

To all whom it may concern:

Be it known that I, ERNEST E. WEBB, a citizen of the United States, residing at Baltimore, in the State of Maryland, have invented certain new and useful Improvements in Attachments for Looms, of which the following is a specification.

My said invention relates to an attachment for looms, particularly looms of the type that are provided with automatic devices for discharging the bobbins when empty and replacing them with full bobbins. In such machines, as is well understood, when an empty bobbin is discharged from the shuttle, the free end of the yarn is left hanging and often is caught by the flying shuttle and carried into the warp resulting in weaving in double and an imperfect spot in the woven fabric.

Various attempts have been made to remove the free end of yarn from the shuttle, as set forth in the patent to Hedler, 1,275,684, but for reasons therein set forth the expedients heretofore resorted to have not been entirely satisfactory.

The object of my said invention is to overcome this trouble and this I accomplish by providing an attachment which is positively actuated throughout and certain in its action for catching this free end of the weft or filling thread and throwing it away from the shuttle box and clear of the flying shuttle.

Referring to the accompanying drawings which are made a part hereof and on which similar reference characters indicate similar parts.

Figure 1 is an end elevation of a portion of a loom showing my improved attachment in the position it occupies thereon, parts of the loom being shown in section for the purpose of more clearly illustrating the construction and arrangement of the parts.

Fig. 2, a detail front elevation showing a portion of the machine and the attachment on an enlarged scale.

Fig. 3, a detail section on the dotted line 3—3 in Fig. 1, and

Fig. 4, a perspective view of one of the parts.

In said drawings the portion marked 10 is the main frame of the loom. Said frame has bearings in which the driving crank-

shaft 11 is journaled and other bearings in which the cam shaft 12 is journaled. On 55 crank 13 of shaft 11 is mounted a pitman rod 14 pivotally connected to the lay 15 of the loom, in the usual manner.

A bobbin magazine 16 with the usual bobbin ejecting mechanism 17, of a common 60 type, is mounted above the lay in the usual manner as shown in Fig. 1.

As will be understood, the mechanism above described is of a usual or any appropriate construction and arrangement and is 65 only illustrated for the purpose of making the construction and arrangement of the attachment and its operation more easily understood. A detailed description of said mechanism is therefore thought to be un- 70 necessary.

My said attachment consists of a member 18 of a form best illustrated in Fig. 4, having a central bearing and mounted to rock on a shaft 19 which is carried by an angle 75 bracket 20 bolted to the side of the frame 10 beneath the magazine 16. The downwardly projecting end 21 of said member 18 is connected by an adjustable connecting rod 22 with a crank pin 23 adjustably mounted 80 in a slot 24 on a crank-arm 25 secured to the cam shaft 12 of the machine.

The other end of member 18 is formed with an L-shaped arm 26 provided with a threaded opening adapted to receive an adjusting screw 27 for a purpose to be presently described. A plate 28 with a hob 29 is mounted to swing on a shaft 30, which is carried by said member 18, and is limited in its movement in one direction by said ad- 90 justing screw 27 and is yieldably held in contact with said adjusting screw by means of a spring 34 secured to a lug 35 on the plate 38 and to a bracket 36, which is secured to the arm 26 by the screw 27. A lock-nut 37 95 on said screw holds the screw and bracket in their proper adjustment. Secured to the plate 28 and extending upwardly therefrom is a plate or arm 31 having a "saw-tooth" upper edge 32 and armed on its front face 100 adjacent to said teeth with a strip of card cloth 33.

In operation the crank shaft 11 operating the lay 15 revolves twice to each revolution of the cam shaft 12, thus causing the lay to 105 have two complete movements to each move-

ment of the member 18 and plate 31. This movement brings the plate 31 to lie beneath the shuttle each time the shuttle is beneath the magazine with a result that when an empty bobbin is ejected from the shuttle and replaced by a full bobbin, the empty one passes over the strip of card cloth 33 which engages the trailing end of the yarn and causes the same to be caught by the teeth 32 and jerked free of the flying shuttle, thereby preventing it from being carried in the warp with the before mentioned disadvantages.

Having thus fully described my said invention, what I claim as new and desire to secure by Letters Patent, is:

1. In a filling replenishing loom, a lay, a shuttle box thereon, a reciprocating thread-catcher adapted to engage the filling between the shuttle-box and the discharged filling-carrier at the time of filling change and means permanently connected to the thread-catcher and to a working shaft of the machine to move the thread-catcher reciprocatingly toward and from the lay, substantially as set forth.

2. In a filling replenishing loom, a lay, a shuttle box thereon, and means for withdrawing the thread end from the shuttle box when filling change takes place comprising a member adapted to engage the face of the lay at the time of change, means on the face of the member to grip the thread and means to move the member constantly to and fro on the loom.

3. An attachment for looms comprising a member mounted to oscillate longitudinally of the loom adjacent to the position where the bobbins are changed and provided with means adapted to catch the trailing thread of the released bobbin, and a connection between said attachment and the machine cam-shaft for operating the same with an accelerated movement at the time of thread engagement, substantially set forth.

4. In a filling replenishing loom, a lay and shuttle boxes, a device adapted to grip the thread between a discharged filling carrier and a shuttle-box and means to reciprocate said device longitudinally of the loom, said means comprising positive connections from the device to the cam-shaft of the loom.

5. An attachment for looms comprising a member pivoted adjacent to the bobbin changing position for movement longitudinally of the loom, a member extending upwardly from said pivoted member armed

with thread-engaging means, and an adjustable connection between said pivoted member and the cam shaft of the machine, substantially set forth.

6. In a filling-replenishing loom, a lay and shuttle-boxes, a member pivoted on the loom frame, a thread-catcher thereon, and connections from said member to a moving shaft of the loom to oscillate the thread-catcher once for every two oscillations of the lay.

7. In a loom, a lay and shuttle-boxes, a member pivoted on the loom frame, a thread-catcher pivoted thereon and adapted to bear against the lay, supporting means on the pivoted member against which the thread-catcher normally rests, yielding means to hold the thread-catcher against the supporting means and a link attached to the pivoted member and to the cam-shaft of the loom.

8. In a loom, the combination with the bobbin-changing mechanism and the lay-operating mechanism, of an attachment comprising a member pivoted adjacent the position where the bobbins are changed, a connection between said member and the cam-shaft of the machine whereby said member is operated once to each two operations of the lay, a member projecting up from said pivoted member formed with a toothed upper edge and armed with thread-engaging means, whereby the trailing thread of the ejected bobbin is caught and held from being carried into the warp by the shuttle, substantially as set forth.

9. A filling thread extracting mechanism for looms, comprising a thread catcher, a pivot therefor, and a pitman adapted to be permanently connected at one end to the thread catcher and at the other end to a crank on a moving shaft of the loom, substantially as set forth.

10. In a filling replenishing loom, means to eject a filling carrier and a device constantly oscillating across the path of ejected filling carriers, said device comprising means to grip the exhausted thread adjacent its end, and withdraw it from the loom, substantially as set forth.

In witness whereof, I have hereunto set my hand and seal at Baltimore, Md., this 22nd day of December, A. D. nineteen hundred and nineteen.

ERNEST E. WEBB. [L. S.]
